100,409

DESIGN FOR A TEXTILE FABRIC

Nathaniel E. Burgess, New York, N. Y.

Application May 11, 1936, Serial No. 62,587

Term of patent 3½ years

To all whom it may concern:

Be it known that I, Nathaniel E. Burgess, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The design is characterized by a series of narrow strips forming part of the background of a fabric and arranged in parallel relation with a series of relatively wide crinkled stripes superimposed on the plain background of the fabric.

I claim:

The ornamental design for a textile fabric, substantially as shown and described.

NATHANIEL E. BURGESS.
